UNITED STATES PATENT OFFICE.

WATSON W. RICH, OF MINNEAPOLIS, MINNESOTA.

DISCHARGE APPARATUS FOR COAL OR ORE BINS.

SPECIFICATION forming part of Letters Patent No. 422,094, dated February 25, 1890.

Application filed December 13, 1889. Serial No. 333,614. (No model.)

To all whom it may concern:

Be it known that I, WATSON W. RICH, a citizen of the United States, residing at Minneapolis, in the county of Hennepin and State 5 of Minnesota, have invented a new and useful Improvement in Discharge Apparatus for Coal or Ore Bins, of which the following is a specification.

My invention relates, more particularly 10 stated, to improved means for effecting the desired counterbalancing of the vertically-adjustable chute at the bin of a coal or ore dock, whereby to raise and lower it shall not require the exertion of power greater or ma- 15 terially greater than is needed to overcome the friction of parts.

The means forming my improvement involve a cable, chain, or other suitable flexible medium connected at one end with the chute, 20 whence it extends to and is engaged by the hoisting mechanism, and having confined upon or secured at intervals to it toward its opposite end counter-weights capable of exerting sufficient resistance to counterbalance 25 or nearly counterbalance the chute in its lowest or discharging position, wherein it offers the greatest resistance, and which counter-weights as the resistance of the chute decreases in its rise are thereby successively 30 neutralized as to their effect upon the chute, and as the resistance of the chute in its de- 35 scent increases are thereby successively "picked up," or brought into position to exert their gravity against the chute.

My improvement is illustrated in the accompanying drawings, in which—

Figure 1 represents an ore or coal dock in broken side elevation, provided with my improved counterbalancing medium in one of 40 its forms. Fig. 2 is a broken view of the upper portion of the dock in front elevation; Fig. 3, a broken sectional view illustrating another form of my improved counterbalancing means; and Fig. 4, a view similar to that 45 presented in Fig. 3, showing still another arrangement of my improved counter-balance.

A is the frame-work of the dock supporting the bin B, from the discharge-opening of which extends, as usual, the pivotal chute or 50 spout C, the bin being surmounted by suitable hoisting mechanism D.

I prefer to provide the common form of the hoisting mechanism illustrated, though any other construction thereof which will serve to operate my improved counter-balance is intended to be included as within my invention. That shown comprises a drum *r* on a rotary shaft *q*, adapted to be turned by a winch *q'*, (shown in dotted lines in Fig. 1,) and journaled in the frame A', and carrying 55 also a smaller drum *p*; and a cable *o* or analogous flexible medium serves to connect the chute from near its forward or free end with the drum *r*.

The parts thus far described involve no 60 features of novelty, being common in the discharge apparatus of coal and ore bins.

E is a cable (though any other form of flexible medium—such as a chain or rope—will answer the same purpose) suspended at one 65 end from the drum *p* in a manner to cause it to be wound upon the last-named drum in turning the shaft *q* to unwind from the drum *r* the cable *o*. Toward its opposite end the cable *E* is provided with weights *F*, secured 70 to it in any manner that will not interfere with its necessary flexibility, and preferably, as shown, at predetermined intervals.

The construction illustrated in Fig. 1 involves a housing or guide-tube *G*, near the 75 base of the dock, and into which the cable *E*, with its weights *F*, extends. At the base of the guide-tube are offsets *n*, *n'*, and *n''* around openings *m*, *m'*, and *m''*, each of a size to admit into it the weight *F*, for which it is provided, the lowest weight being the smallest 80 and the size of the others increasing in order, as shown. Then when the weights are at their lowest positions the first rests on the base of the opening *m*, the second on the offset *n* around the base of the opening *m'*, the third on the offset *n'* around the base of the opening *m''*, and the fourth around the offset *n''* at the top of the opening *m''*. The number of the weights and of the rests for them 85 may of course be regulated according to particular desire or requirement.

By turning the shaft *q* in a direction to effect raising of the chute *C* the weights *F* will come to rest on their respective supports successively, thereby decreasing their resistance 90 to that of the chute as or substantially as

the resistance of the chute decreases in its rise. In lowering the chute toward its position for the discharge, whereby its resistance gradually increases, the weights F are raised 5 in turn from the lowermost upward, or "picked up," all, or all that are required, being suspended when the chute reaches its lowest or operative position, wherein it presents the greatest resistance, and at which it is indicated in Fig. 1.

The modification illustrated in Fig. 3 involves the same principle as the construction already described, the difference being that the cable E instead of being free at its weight- 15 ed end is fastened at a point x, to which it just or a little more than reaches when the opposite end is wound to or nearly to the full extent on the drum p, and the chute occupies its lowest position. Then all the weights F 20 are suspended from the drum p and resist the chute, which, in being raised and thus presenting less and less resistance, entails unwinding of the cable E, which causes more and more of its length to hang suspended 25 from the point x until when the chute reaches its highest position all the weights may be so suspended, where their effect on the chute is neutralized. In Fig. 4, where- 30 in the various positions assumed by the chute in describing its arc are indicated by the dotted lines 1 to 4, inclusive, the principle of the mechanism is the same as of that described with reference to Figs. 1 and 3, the operation being substantially like that of the 35 apparatus in Fig. 1—namely, that the effect of the weights is gradually neutralized or brought into play according as the chute is raised or lowered, by stopping or intercepting them on a suitable support in the one in- 40 stance and picking them up successively in the other instance.

The same principle may be applied in various other modified forms, all of which I desire to be understood as included within my 45 invention.

What I claim as new, and desire to secure by Letters Patent, is—

1. In a discharge apparatus for coal and ore bins, the combination, with the chute C and its hoist D, of a cable E, suspended from the hoist and provided toward its lower end with a series of weights F, and means, substantially as described, for neutralizing, as the chute is raised, the resistance to it of the weights in succession, and for bringing them 55 successively into play against the resistance of the chute as it is lowered, substantially as and for the purpose set forth.

2. In a discharge apparatus for coal and ore bins, the combination, with the chute C and its hoist D, comprising a rotary shaft q, carrying the drum r, connected with the chute by the cable o, and the drum p, of a cable E, suspended from the drum p to be wound thereon by lowering of the chute, and provided toward its lower end with a series of weights F, and means, substantially as described, for neutralizing as the chute is raised the resistance to it of the weights in succession, and for bringing them successively into 70 play against the resistance of the chute as it is lowered, substantially as and for the purpose set forth.

3. In a discharge apparatus for coal and ore bins, the combination, with the chute C and its hoist D, comprising a rotary shaft q, carrying the drum r, connected with the chute by the cable O, and the drum p, of a cable E, suspended from the drum p to be wound thereon by lowering the chute, and provided 75 toward its lower end with a series of weights F, and a series of supports for the weights, one above the other, below the said weights, the whole being constructed and arranged to operate substantially as described.

WATSON W. RICH.
